UNITED STATES PATENT OFFICE.

ROBERT L. ELLERY, OF TOLEDO, OHIO.

SCREW-THREAD GAUGE.

Application filed February 26, 1920. Serial No. 361,389.

To all whom it may concern:

Be it known that I, ROBERT L. ELLERY, a citizen of the United States, and a resident of Toledo, in the county of Lucas and 5 State of Ohio, have invented a certain new and useful Screw-Thread Gauge; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to lead test gauges for the threads of screws, taps, and similar articles, and has for its object the provision of a simple, improved and efficient apparatus of this character which is capable of easily 20 and quickly finding any error in the lead of threads in articles of the class described and is adjustable to suit threads of different lengths and diameters.

The invention is fully described in the 25 following specification, and while, in its broader aspect, it is capable of embodiment in numerous forms, a preferred embodiment thereof is illustrated in the accompanying drawings, in which,—

30 Figure 1 is a top plan view of an apparatus embodying the invention with a screw or tap in thread gauging relation thereto. Fig. 2 is a side elevation thereof with a part broken away. Fig. 3 is a front end elevation of the apparatus, and Figs. 4 and 5 are fragmentary sections taken substantially on the lines 4—4 and 5—5 respectively in Fig. 3.

Referring to the drawings, 1 designates the frame of the apparatus, which frame is 35 illustrated, in the present instance, as of substantially triangular form and with its interior hollow. The frame at its front end, or that which is opposite the apex thereof, is provided in its upper portion with a horizontal slideway 2 and below said slideway with a vertical slideway 3. In the slideway 2 is mounted a slide block 4, the adjustment of which within the slideway lengthwise thereof is controlled by a screw 5, which is 40 threaded in the block and has its outer end projected through an end plate 6 of the frame for rotary but not longitudinal movements therein and provided without said plate with a control head 7. The slide block 4 is provided adjacent to its inner end with

a forwardly projecting point 8 for projecting into the thread groove of a screw, tap or other article which is being tested to determine any error in its thread. The point 8 forms the fixed thread engaging 60 member of the gauge.

The movable thread engaging member of the gauge comprises a point 9 disposed in normal predetermined horizontal spaced relation to the fixed point 8 at the inner side 65 thereof and is carried at the free end of a lever 10, which projects rearwardly into the frame 1 and is fulcrumed at its rear end in the apex portion of the frame for horizontal pivotal movements. The free end of 70 this lever has an upper and lower bearing in the inner end portion of the slideway 2, which permits a limited horizontal movement of the lever but prevents a vertical movement thereof. The lever 10 is provided 75 adjacent to its forward or free end with an upwardly or forwardly projecting finger 11 which has lateral engagement with a gauge plunger 12 at a point in substantial vertical alignment with the point of engagement of 80 the lever point 9 with a thread. The gauge 13 with which the plunger 12 is connected is of the extremely sensitive type and is adapted to move the indicator finger 14 85 thereof upon the slightest movement of the 85 lever 10 from normal position. As gauges of this character are old and nothing novel is claimed therefor the gauge is not shown in detail.

It is preferable to provide the inner end 90 of the lever 10 with a vertical bearing portion 15 having conical bearing sockets in its opposite ends with which the respective opposed conical bearings 16, 16 engage. These bearings are mounted for vertical adjustment in a sleeve 17 secured within the frame 1 and are vertically adjusted therein by means of respective set screws 18 which thread through the closed ends of the sleeve. The lever 10 projects transversely into the 100 sleeve 17 through an opening 19 in its side. The advantage of mounting the lever in this manner is not only to provide a perfect pivotal bearing therefor but also to facilitate an adjustment thereof to prevent any binding action of the forward end portion of the lever in the slideway 2.

The screw, tap or other work-piece *a* being gauged is intended during the gauging operation, to rest on a table 20 with its axis 110

55 4 is provided adjacent to its inner end with

in the plane of engagement of the points 8 and 9 therewith. The table is provided at the upper end of a bracket 21, which has its lower end mounted for vertical adjustment 5 in the frame slidway 3. The vertical adjustment of the bracket 21 to change the position of the table 20 relative to the gauge points to suit the diameter of the work-piece being gauged, is effected by a screw 22, which projects down through an opening in the top 10 of the frame and is threaded into a projection 23 on the inner side of the slide portion of the bracket 21.

It is preferable in practice to have the 15 lever 10 of considerable length, as shown, as more accurate gauging is thereby obtained due to the movement of the point 9 approaching more nearly a straight line than would otherwise be the case and obtaining the 20 advantages of a gauge slide while avoiding objections incident to the use thereof.

It is evident that I have provided a simple 25 and efficient lead test gauge for the threads of screws, taps, or similar articles; that the fixed member of the two gauge points is adjustable to suit the length or size of the thread to be gauged and to suit the master screw, and that the movable gauge point is carried by a lever through which any relative movement of the gauge point by reason 30 of an error in the thread being gauged will be communicated to the coacting member of an error indicating gauge 13. It is found in practice that with this gauge an error of twenty thousandths of an inch or less in the 35 thread will be accurately registered on the gauge by the movement of its indicator.

I wish it understood that my invention is not limited to any specific construction, 40 arrangement or form of the parts, as it is capable of numerous modifications and changes without departing from the spirit of the claims.

Having thus described my invention, what 45 I claim as new, and desire to secure by Letters Patent, is,

1. In a screw thread gauge, means for supporting a work piece the screw thread of which is to be gauged, a fixed point and a movable point for axially spaced coaction 50 with the threads of a work piece when mounted on the supporting means, the fixed point being carried by said means, a lever carrying the movable point for movements axially of a work piece disposed in gauging 55 position on the supporting means, and means connected to the lever at substantially the same distance from its fulcrum as the movable point and operable by movements of the

lever to indicate any relative movement of the points.

2. In a screw thread gauge, a support for a work piece the screw thread of which is to be gauged, a pair of work thread gauging points one of which points is fixed and the other movable and spaced axially of a work piece to be gauged, means carrying the fixed point and manually adjustable to suit the length or size of a thread to be gauged and of a master screw, a member mounted for free horizontal swinging movements and carrying the movable point a considerable distance from the axis of the swinging member, and means connected to the member at substantially the same distance from the axis thereof as the movable point and operable by movements of the member to indicate any relative movements of the points when engaged with a work piece.

3. In a screw thread gauge, a frame, a work support carried on the frame for vertical adjustment, a member carried for horizontal adjustment by the frame over and adjacent to the support, separate means operable to respectively adjust the support and member, a fixed work thread gauge point carried by the member, an arm of considerable length mounted for free horizontal swinging movements and having a movable work thread gauge carried by the arm in adjacent horizontal spaced relation to the fixed point, the points being spaced axially of a work piece disposed in gauging position on the support, and means acted on by the arm adjacent to the movable point in laterally spaced relation thereto to indicate any relative movement of the points during a gauging operation.

4. In a gauge apparatus of the class described, a frame having a horizontal slide-way therein, a slide block in said way, means manually operable to adjust the slide block, a fixed gauge point carried by said block for adjustment therewith, a lever fulcrumed in the frame at a distance from said fixed point rearwardly thereof and mounted for horizontal swinging movements transverse to said point, a movable gauge point carried by said lever at a side of the fixed point, means acted on by the lever to indicate any relative movement of the points during a gauging operation, and an adjustable means for supporting a work-piece in gauging relation to said points.

In testimony whereof, I have hereunto signed my name to this specification.

ROBERT L. ELLERY.
